[57] CLAIM

The ornamental design for a heat dissipation fan, as shown and described.

DESCRIPTION

FIG. 1 is a perspective view of a heat dissipation fan showing a first embodiment of my new design; FIG. 2 is a top plan view thereof; FIG. 3 is a right side elevational view thereof; FIG. 4 is a front elevational view thereof; FIG. 5 is a rear elevational view thereof; FIG. 6 is a left side elevational view thereof; and FIG. 7 is a bottom plan view thereof. FIG. 8 is a perspective view of a heat dissipation fan showing a second embodiment of my new design; FIG. 9 is a top plan view of FIG. 8; FIG. 10 is a right side elevational view of FIG. 8; FIG. 11 is a front elevational view of FIG. 8; FIG. 12 is a rear elevational view of FIG. 8; FIG. 13 is a left side elevational view of FIG. 8; and, FIG. 14 is a bottom plan view of FIG. 8.
